UNITED STATES PATENT OFFICE

2,439,878

GUNNER'S TURRET FOR AIRCRAFT

Julius G. Villepigue, Inglewood, Calif., assignor
to North American Aviation, Inc., Inglewood,
Calif., a corporation of Delaware

Application February 21, 1944, Serial No. 523,230

8 Claims. (Cl. 89—37.5)

1

This invention relates to gunners' turrets for aircraft and has as its general object to provide an improved turret mechanism adaptable particularly for the nose of a military plane.

A more specific object of the invention is to provide a turret arrangement which permits the gunner to have maximum target visibility. To this end, the invention provides an arrangement in which the gunner may operate in a kneeling position, with his head and the upper portion of his body extended in the direction of fire, and with his eyes positioned well forward of the center of the turret.

Another object of the invention is to provide a turret that affords a double armored protection for the gunner.

Another object is to provide a turret arrangement in which the gunner may have direct visibility through a window at the outermost extremity of the turret, and in which such window may be of armor glass and arranged to form the outer extremity of an armored cavity inside the turret, in which the upper portion of the gunner's body may be accommodated.

Another object of the invention is to provide a turret, which provides for bodily oscillation of the turret, either in azimuth or in elevation, under local control of the gunner.

A further object of the invention is to provide a turret incorporating novel mechanism for bracing the turret against gun recoil, while permitting oscillation of the turret in azimuth or in elevation. To this end, the invention provides an arrangement wherein the turret is mounted for oscillation in elevation on a horizontal axis with reference to a yoke which in turn is mounted for oscillation on a vertical axis and is braced by a bracing arrangement extending rearwardly and cooperating, with rolling contact, with an arcuate track carried by a fixed portion of the fuselage.

In the drawings, like reference characters designate similar parts in the several views.

Fig. 1 is a plan view, in horizontal section, of a turret mechanism embodying the invention;

Fig. 2 is a front elevation view of the same;

Fig. 3 is a vertical longitudinal sectional view of the same; and

Fig. 4 is a vertical transverse sectional view of the same, taken on the line 4—4 of Fig. 3.

As an example of one form in which the invention may be embodied, I have shown in the draw-

2

ings a turret arrangement in the nose portion of a military airplane, indicated generally at 10. The turret 12, of parti-spherical shape, is mounted for oscillation in elevation, around a horizontal axis, upon trunnions 14 carried by a yoke 16. The yoke 16 has a spindle 18 extending upwardly and journaled at its upper end in a bearing 20 mounted in the fuselage nose portion 10. The lower end of the spindle 18 is mounted in a bearing 19, which is carried by a tubular support 21 secured to the fuselage nose portion 10 by means of a bracket 23. To the yoke 16 is secured a tripod brace 22, which extends rearwardly and carries a series of rollers 24. The rollers 24 cooperate with an arcuate track 26 which is mounted in a horizontal plane in the nose portion 10, being anchored to one of the bows 28 thereof. The track 26 is formed on an arc of a circle concentric with the vertical axis of the shaft 18, and thus permits the yoke 16 to rotate about the vertical axis while bracing it against gun recoil, which is transmitted directly from the cylinder 32 to the tripod 22.

The turret 12 includes the parti-spherical shell portion 30 which is of light armor-plate construction, and a cylinder 32, also of armor plate, which is, in the normal turret position shown, coaxial with the longitudinal axis of the fuselage 10. The forward end of the cylinder 32 is secured to the shell 30, and an intermediate region thereof extends through and is supported by a bulkhead 34 of armor plate, the periphery of which is attached to the shell 30. The forward end of the cylinder 32 is closed by a window 44 of armor glass. The upper and lower regions of the rear portion of the cylinder 32 are cut away as at 35 and 37 to provide the spaced extensions 33. The cut away spaces 35 and 37 accommodate, respectively, the tubular support member 21 and the body of the operator referred to hereinafter. The extensions 33 carry opposed bearings 36 by means of which the cylinder, and thus the entire turret, is mounted upon the trunnions 14 for oscillation in elevation.

In the upper region of the shell 30 is an arcuate slot 38, through which the tubular bracket 21 extends, the slot 38 being of sufficient length to permit the turret to oscillate in elevation through the desired range. A cover plate 39, carried by the bracket 21, closes the slot 38. The rear portion of the shell is open as at 40.

Four machine guns 42 are mounted upon the

linder 32 and project through the forward extremity of the shell 12.

In the lower region of the shell 12 is a floor member 46 which supports a cushion 48, on which the gunner 50 may kneel, with the upper portion of his body projecting forwardly into the cylinder 32. Thus the gunner's eyes may be positioned close to the window 44 for maximum target visibility, while the vital portions of the gunner's body are protected within the armored wall of the cylinder 32. Added armored protection is provided by the bulkhead 34, the window 44, and the shell 30.

The gunner is supported in this reclining position by a seat 52, which is mounted on an arm 54 and hinged at 56 to the floor member 46. The seat may be folded rearwardly and downwardly to permit the gunner to enter and leave the turret.

Defined between two spaced bulkheads 59 and 61, located centrally of the turret, in planes extending transversely of the axis of the cylinder 32, in an annular space in which is accommodated a pair of upper ammunition magazines 58 and a pair of lower ammunition magazines 60 (Fig. 4). The upper regions of the bulkheads 59 and 61 are formed with channelled portions 63 and 65 respectively, adapted to accommodate the tubular support 21 when the turret is oscillated in elevation. The channelled portion 65 is cut away as at 67 to accommodate the upper turret operating motor which will be referred to hereinafter. This cutaway space 67 in the rear bulkhead is extended laterally sufficiently to give access to the upper magazines 64 for loading the same.

The bulkheads 59 and 61 are annular in form with the exception that they are cut away below the cylinder 32 to provide a space 69 to accommodate the floor member 46 and the gunner's legs, as indicated in Fig. 2. In Fig. 4 the forward bulkhead 59 is removed to show the operating mechanism therebehind.

The empty cartridge cases are ejected through chutes 66 and 68 respectively which are bent rearwardly and extended through the rear bulkhead 61 so as to discharge into the spaces on either side of the gunner. These spaces may, if desired, be suitably inclosed so as to provide receptacles for the cartridges.

For oscillating the turret in elevation, I provide a motor 70 carried by an extension 33 of cylinder 32, and a worm and gear unit 72. This worm and gear unit may embody a casing 74 formed as part of a bearing 36, a worm (not shown) carried by the shaft of the motor 70 and a worm wheel 76 (Fig. 4) rigidly secured to a trunnion 14 of the yoke 16.

Oscillation of the turret in azimuth is provided for by a motor 78 mounted on an extension 80 of the bracket 23. Carried by the motor shaft is a worm 82 which meshes with a worm gear 84 attached to the spindle 18.

Being built into the turret structure, these motor devices lend themselves readily to being locally controlled by the operator.

The foregoing may be taken as illustrative of one form in which the invention may be embodied, it being my intention to cover in my claims the use of any equivalent arrangement or apparatus.

I claim as my invention:

1. Aircraft turret construction comprising an outer wall of parti-spherical shape, a tubular inner wall disposed within said outer wall and adapted to receive the upper portion of a gun-

ner's body, means for supporting said outer wall for oscillation in the azimuth and in elevation and a window in said outer wall in registering with one end of said tubular inner wall.

5 2. Aircraft turret construction comprising an outer wall of parti-spherical shape, a tubular inner wall disposed within said outer wall and adapted to receive the upper portion of a gunner's body, a window in said outer wall registering with one end of said tubular inner wall, and a plurality of guns disposed in spaced array about and carried by said tubular inner wall, said guns projecting through said outer wall.

10 3. Aircraft turret construction comprising an outer wall of parti-spherical shape, a tubular inner wall disposed within said outer wall and adapted to receive the upper portion of a gunner's body, a window in said outer wall registering with one end of said tubular inner wall, and means upon which the inner end of said tubular inner wall is journaled for supporting said turret for oscillation in azimuth and in elevation about a horizontal axis.

15 4. Aircraft turret construction comprising a parti-spherical outer wall of armor plate, a cylindrical inner wall, one end of which is attached to said outer wall and is provided with a disk of armor glass forming a window in said outer wall, a plurality of guns carried by said cylindrical inner wall in spaced array therearound and projecting through said outer wall, and means for supporting a gunner in a kneeling position with the upper portion of his body extending into the space within said cylindrical inner wall and toward said window.

20 35 5. Turret construction as defined in Claim 4, including a bulkhead of armor plate the periphery of which is attached to said outer wall and the inner region of which supports the intermediate portion of said cylindrical inner wall.

40 6. Turret construction as defined in Claim 4, including means on which the opposite end of said cylindrical inner wall is journaled for supporting said turret for oscillation in elevation about a horizontal, transverse axis.

45 7. Aircraft turret construction comprising a parti-spherical outer wall, a cylindrical inner wall, an armor ring in which the intermediate portion of said inner wall is supported, the periphery of said ring being attached to said outer wall, machine guns mounted in spaced array upon and about said inner wall, and ammunition magazines disposed in the annular space between said inner and outer walls and rearwardly of said ring.

55 8. Aircraft turret construction comprising, in combination with a fuselage, a yoke including a normally upwardly projecting spindle and means, carried by said fuselage, in which said spindle is mounted for oscillation on a normally vertical axis, a turret suspended upon said yoke for oscillation in elevation about a normally horizontal axis, a plurality of guns mounted so as to transmit their recoil to said yoke, bracing means having one end attached to said yoke and arranged to oppose the recoil transmitted to the yoke, and an arcuate track carried by the fuselage, said bracing means having means for making rolling abutment with said track for transmitting said recoil thereto while permitting the yoke to oscillate about said vertical axis.
